SHEET FOLDING MACHINE

James H. Roberts, Zanesville, and Charles V. Achauer, Philo, Ohio, assignors to Hazel-Atlas Glass Company, Wheeling, W. Va., a corporation of West Virginia

Application March 8, 1933, Serial No. 660,054

15 Claims. (Cl. 93—49)

This invention relates to sheet folding apparatus and more especially to an automatic mechanism for folding corrugated paper blanks of the type used in shipping box construction.

5 The primary object of the invention resides in simplifying and generally improving prior devices of this type; in insuring the production of a properly and accurately folded blank and in providing readily operated adjustments for 10 easily and quickly adapting the mechanism to blanks of varying sizes.

Other objects and advantages of the construction will be apparent to those skilled in the art, from the following description when taken in 15 connection with the accompanying drawing; in which,

Figure 1 is a perspective view of the mechanism with parts broken away for the sake of clearness, and

20 Figure 2 is a more or less diagrammatic view of the feed mechanism for the blank in its initial form and in its folded form.

Referring to the drawing in more detail the 25 numeral 1 indicates a table of any conventional construction on which the feeding and folding mechanism is mounted. At the left of table 1 a stack of blanks 2 is shown as mounted behind a cross bar 3 which is supported in spaced relation to the table by brackets 4. Vertically adjustable 30 plates 5 are supported on the cross bar 3 and serve to permit the lowermost blank of the stack 2 to be fed forward to the folding mechanism; it being understood of course that the adjustment provides for blanks of different thickness.

35 Also mounted on the crossbar 3 are brackets 6, which are adjustable horizontally and which engage the ends of the stack 2 to maintain it in proper condition. The brackets 6 are provided with fingers 7 which extend forwardly of the cross-bar 3 and act as guides for the blanks as 40 they begin their travel to the folding apparatus.

The table 1 is provided with a pair of longitudinal openings in which feed chains 8 are 45 mounted. These chains are carried on sprocket wheels 9 fixed to shafts 10 below the table top, and are provided with suitably spaced blocks or dogs 11. As will be seen these blocks 11 are arranged in pairs so that the lowermost blank in the stack will be simultaneously engaged at two 50 points and be carried forward in proper position by the movement of the chains. Additional feed chains 12 are shown as spaced laterally from the chains 8. The purpose of these chains is to assist in the feeding of blanks which are substantially larger than those shown in the drawing.

When smaller blanks are being operated upon the blocks or dogs 11 of the chains 12 may be removed so as to avoid interference with other operations and the chains may be covered, if desired, with thin metal plates.

5 As the blanks pass forward from the stack 2 they first pass beneath a pair of presser plates 13 which engage the blanks inwardly of their fold lines and press them against the table surface while the end portions of the blanks are 10 being folded into place. The plates 13 are suspended from above and are adjustably mounted to adapt them to different sizes of blanks as well as to different positions of the fold lines. The support and adjustment of the presser plates 15 will be described hereinafter.

The numeral 14 indicates a pair of folders for bending up the end flaps of the blanks and thereafter turning them down on the body portion. These members extend longitudinally of the table 20 1 and are supported by brackets 15 carried by laterally adjustable plates 16. Each member 14 consists of a narrow strip or band of metal which has its middle portion secured to the brackets 15. The forward ends of these strips are bent outwardly and downwardly into contact with the top of the table while the rearward ends of the strips are bent inwardly and downwardly. It will be apparent therefore that the ends of the blanks will ride up the forward ends of the folders (bending 25 30 at the weakened lines provided in the blanks) until they reach the vertical positions indicated in Figure 1. As the blanks advance further toward the rear of the table the flaps will be bent inwardly and downwardly, following the contour 35 of the rear ends of the folders, until they are pressed flat against the body portion of the blank.

During this advancement of the blank its central portion is held against the surface of the table by the pressed plates 13 which are adjusted 40 to engage the blank slightly inwardly of its fold lines. It is highly desirable that some means be provided to engage the interior upper surface of the blank at the fold lines so as to produce a neat fold and prevent the bulging or breaking down 45 of the surface or skin of the blank at the crease. To this end a plurality of arms or fingers 17, 18 and 19 are pivotally mounted on the presser plates 13. The ends of these fingers are forced outwardly 50 toward the fold lines by any desired means. This is accomplished in the particular apparatus illustrated, by a coil spring 20, which extends from the other end of the finger to a bracket 21, fixed to the presser plate. As will be apparent, the operative ends of the fingers will be constantly 55

pressed against the blank along the lines where it is being creased or folded, thus insuring the desired neatness and exactness of the crease. It is to be noted also that these elements 17, 18 and 5 19 are mounted entirely on the presser plates 13 and hence bear the same relation to the fold lines so long as the presser plates are adjusted to the proper position for the particular series of blanks being operated upon.

10 For the purpose of guiding the blanks as they are advanced toward the end of the table in their passage through the folding mechanism, guide bars 22 are provided. These bars rest upon the table 1 and are resiliently connected to the laterally adjustable plates 16. The connections between the guide bars 22 and plates 16 consist of rods 23 which are fixed at their inner ends to the guide bars and have their outer ends passed loosely through openings in brackets 24. Coil springs 25 surround the rods 23 and have their respective ends in engagement with one of the brackets 24 and a collar 26, thereby providing the necessary resiliency for the bars 22. Nuts 27 may be employed for adjusting the amount of compression in the springs 25.

15 The plates 16 to which the guide bars 22 are connected and which also form supports for the brackets 15 and folders 14, are adjustably connected to the table 1 by means of the transversely extending slots 28 in the table top and the bolts 29 which project from the plates into the slots. Lugs 30 are threaded onto the lower ends of the bolts 29 and serve to lock the plates in adjusted position. To provide for rapid and accurate adjustment of the plates 16 the opposed lugs 30 are provided with right and left hand threads respectively which receive similarly threaded shafts 31. These shafts carry sprocket wheels 32 on which are mounted chains 33, and a crank arm 34 is secured to one of the shafts. It will thus be seen that all of the shafts are operated simultaneously and to the same extent so that the plates 16 as well as the guide bars 22 are moved to the same extent in opposite directions, and are always maintained in parallel relationship during the adjustment. After the plates are properly adjusted they are secured in such position by tightening up on the bolts 29.

20 If it should happen, for one reason or another, that some of the blanks are not accurately folded in passing through the folding mechanism, i. e., one or more of the flaps may be slightly askew, it is highly desirable that they be trued or aligned before the blank leaves the apparatus. For this purpose a feed chain 35 is provided with dogs 36 which extend above the table a distance equal to or greater than the thickness of the folded blank.

25 In the specific form illustrated, the chain 35 is driven from any desired source of power, and this chain 35 drives chains 8 by means of sprockets 37, 37' and sprocket chain 37''. It will be noted (Fig. 2) that the sprocket 37 is substantially smaller than the sprocket 37' so that the feed chain 35 will have a greater speed than the feed chains 8. The forward end of the chain 35 is located a substantial distance forward of the rear ends of chains 8 and the dogs 36 are so spaced on the chain 35 that by reason of the differences in speed between the two a dog 36 will rise up behind a pair of the dogs 11 and gradually overtake them. The dog 36 then assumes the propelling force for the folded blank and by reason of its height presses against the edges of the

folded blank as well as against the edge of the main body portion.

20 This pressure of the dog 36 on the edge of the folded blank tends to straighten out any unevenness in the blank. This action of the dog 36 is increased somewhat by a certain resistance transmitted to the folded blank by a presser plate 38 adjustably suspended from a superstructure which will now be described.

25 The superstructure comprises a plurality of standards 39 which have their lower ends fixedly secured to the top of the table. The upper ends of the standards are connected and braced by longitudinally and transversely extending rails 40 and 41. The two rails 41 adjacent the rear 15 of the table form a guideway or track for a slidably-mounted carriage 42, from which are suspended a pair of rods 43. The presser plate 38 is secured to the lower ends of rods 43, and its vertical position may be adjusted by means of nuts 44 threaded to the upper ends of the rods, above and below the cross bar of the carriage 42. Adjustment of the carriage transversely of the table is provided by a horizontal shaft 45 which has its inner end in threaded engagement 20 with a bearing 48 on the carriage. The outer end of the shaft passes through a bearing 47 on the rail 40 and is provided with a crank 46. The shaft 45 is held against longitudinal movement by any desired means, as by collars arranged on both sides of the bearing 47. Rotation of the crank 46 and shaft 45 will impart movement to the carriage 42 toward or away from the center line of the table, depending upon the direction of rotation of the shaft. By this adjustment it 30 will be seen that the presser plate 38 may be readily adjusted so as to cause the same to engage the free ends of the flap as the folded blank is advanced along the table. The degree of pressure applied by plate 38 to the blank and hence the degree of resistance of the blank to movement by the dog 36 may be varied by adjusting the nuts 44 to vary the distance between the plate 38 and the surface of the table.

35 While the plate 38 functions to compress the free ends of the flaps of the blank against the body thereof, it is highly desirable that pressure be applied to the folded edges of the blank so as to set them, and to provide sharply defined creases at those points. For this purpose a pair 40 of presser rolls 49 is mounted adjacent the rear end of the table. These rolls are loosely mounted on the shaft 50 which is spaced above the table 1 and extends across the path of travel of the blanks. Bolts 51 extend through apertures in 45 the ends of shaft 50 and are anchored to the top of the table. The resilient mounting for the shaft comprises pairs of springs 52 and 53 surrounding each bolt; one of the springs being below and the other above the shaft. By means of 50 this construction the desired pressure is applied to the folded edges of the blanks and sets the blank in folded form prior to its passage to conveying apparatus.

55 The rolls 49 must be adjustable of course to suit various sizes of blanks and means has been provided for taking care of this adjustment simultaneously with the adjustment of the guide rods 22 and folders 14. This means consists of annular grooves 55 formed in the hubs of the rolls 49 and arms 56 fixed to the ends of the guide rods 22. The free ends of the arms 56 project into the grooves 55 and it will be obvious that 60 adjustment of the rods 22 will provide a similar 65 adjustment of the rolls 49.

and equal adjustment of the rolls 49, so that the latter always bear in fixed relation to the guide rods.

The presser plates 13, for the blanks in the first stages of their processing, are suspended from the superstructure of the apparatus in a manner similar to the plate 38. This suspending means comprises a pair of rods 57, 58, for each plate, which rods have their ends secured to the plates. The upper ends of the rods 57-58 are threaded and are adjustably secured to cross bars 59 by means of nuts 60. The plates 59 are slidably mounted on the two forward rails 41 of the superstructure and are each provided with threaded bearings 61. Bearings 62 on each of the side rails 40 are aligned with the bearings 61 and provide supports for pairs of shafts 63 which have their inner ends threaded into the bearings 61. Rotative force may be applied to shafts 63 through cranks 64, and by this means the presser plates are adjusted toward or away from the center line of the table depending upon the size of the blanks being operated upon or upon the width between the fold lines. The shafts 63 are held against longitudinal movement by any desired means, as by collars on both sides of the bearings 62.

The operation of the apparatus will now be briefly described, it being assumed that the various adjustments have been previously made to adapt the device to the particular blanks being operated upon. As a pair of dogs 11 reaches the stack of blanks 2 the lowermost blank will be carried under the plates 5 and guided by fingers 7 to the presser plates 13. Further movement of the blank will cause the end portions thereof to ride up the inclined portions of the folder 14 until they reach the vertical positions indicated at the center of Figure 1. Further advancement of the blank will bring the flaps under the downwardly and inwardly curved ends of the folders 14 so that the blank will assume the folded condition indicated at the right of Figure 1. During the folding of the flaps in the manner just mentioned pressure is applied to the inner edges of the folds by the spring fingers 17, 18 and 19 which prevents the bulging of the inner facing of the blank and provides neat and sharp creases.

During and after the folding operations the blanks are maintained in proper positions by the adjustable guide bars 22. Advancement of the blanks is made by the pairs of dogs 11 until the blanks pass from under the pressure plates 13 and folders 14. At that time the feed chain 35 causes one of the dogs 36 to take up the feeding of the blank, and by reason of the fact that this dog is of sufficient height to press against the edges of the folds of the blank a truing or aligning of the flaps is provided for. This truing of the folded blank is materially assisted by the presser plate 38 which tends to retard movement of the blank and hence provides the necessary force to bring the flaps into alignment. After leaving the presser plate 38 the folded blank passes under the resiliently mounted presser rolls 49 where the creases in the blank are given a more or less permanent "set".

From the above description and accompanying drawing it will be apparent to those skilled in the art that we have provided an automatic folding mechanism which is a very substantial simplification of prior devices; that it may be easily and quickly adjusted to adapt it to blanks of various sizes as well as various dimensions of

flaps; that the folding mechanism for the blanks is constructed to provide a neat crease in the material; and that the feeding mechanism is so designed as to impart a pressure to the edges of the folded flaps to realign or true any blanks which may have become distorted. 5

In accordance with the patent statutes we have described what we now believe to be the preferred form of construction, but obviously many modifications and changes may be made without departing from the spirit of the invention and all such modifications and changes are intended to be included within the scope of the appended claims. 10

What we claim is:

1. A blank folding machine including a table, means for advancing the blanks in succession across the table, means for folding the blanks as they are advanced, and means carried by the advancing means for engaging the edges of the folded blanks for truing the same, said truing means being movable relative to the folded blank in the direction of the line of travel. 15

2. A blank folding machine including a table, means for advancing the blanks in succession across the table, means for folding the blanks as they are advanced, means for pressing the folded blank, and means carried by the advancing means for engaging the edges of the folded blank for truing the same, said truing means being 20 movable relative to the folded blank in the direction of the line of travel. 25

3. A blank folding machine including a table, means for advancing the blanks in succession part way of the length of the table, means for folding the blanks as they are advanced, means for pressing the folded blanks, and means engaging the folded blank for truing it and pushing it to the end of the table, said truing means having a height at least substantially equal to 30 the thickness of the blank when folded, and said truing means being movable relative to the folded blank in the direction of the line of travel. 35

4. A blank folding machine including a table, means for advancing the blanks in succession part way of the length of the table, means for folding the blanks as they are advanced, means for pressing the folded blanks, a conveyer, a dog on the conveyer for engaging the edges of the folded blank for truing it and pushing it 45 to the end of the table, said dog having a height substantially equal to the thickness of the folded blank, and said dog being movable relative to the folded blank in the direction of the line of travel. 50

5. A blank folding machine including a table, an endless conveyer, a plurality of dogs on the conveyer projecting above the table for engaging the blanks to advance them in succession along the table, means for folding the blanks, a second 55 conveyer, a plurality of dogs on the second conveyer, said last-mentioned dogs having a height at least substantially equal to the thickness of the folded blank, said second conveyer extending beyond the first-mentioned conveyer, and means 60 for driving the second conveyer at a greater speed than the first conveyer, for the purpose described. 65

6. A blank folding machine including a table, means for advancing the blanks in succession along the table, means for pressing the blank 70 against the table as it is advanced, means for folding the blank, and means pressed outwardly engaging the fold lines of the blank as it is being folded.

7. A blank folding machine including a table, 75

- means for advancing the blanks in succession along the table, means for pressing the blank against the table as it is advanced, means for folding the blank, and spring fingers mounted on the blank-pressing means for engaging the fold lines of the blank as it is being folded.
8. A blank folding machine including a table, means for advancing the blanks in succession along the table, means for pressing the blank against the table as it is advanced, means for folding the blank, and a series of spring-pressed fingers for engaging the fold lines of the blank as it is being folded.
9. A blank folding machine including a table, means for advancing the blanks in succession along the table, a pair of plates for pressing the blank against the table as it is advanced, means for folding the blank, and a series of spring-fingers mounted on each plate for engaging the fold lines of the blank as it is being folded.
10. A blank folding machine including a table, means for advancing the blanks in succession along the table, means for folding the blanks as they are advanced, guide bars for the blanks as they are being folded and advanced along the table, and spring-mounted pressers for engaging the folded edges of the blanks after they leave the folding mechanism.
11. A blank folding machine including a table, means for advancing the blanks in succession along the table, means for folding the blanks as they are advanced, adjustably-mounted guide bars for the blanks as they are being folded and advanced along the table, spring-mounted pressers for engaging the folded edges of the blanks after they leave the folding mechanism, and connections between said guide bars and pressers.
12. A blank folding machine including a table, means for advancing the blanks in succession along the table, means for folding the blanks as they are advanced, adjustably-mounted guide bars for the blanks as they are being folded and advanced along the table, a spring-mounted shaft at the rear of the table, and extending across the path of the blanks, presser rolls loosely mounted on the shaft for engaging the folded edges of the blanks after they leave the folding mechanism, and connections between the guide bars and rolls.
13. A blank folding machine including a table, means for advancing the blanks in succession along the table, means for folding the blanks as they are advanced, a pair of plates slidably mounted on the table, a guide bar for the blanks resiliently connected to each plate, and means for simultaneously adjusting said plates toward or away from the center line of the table.
14. A blank folding machine including a table, means for advancing the blanks in succession along the table, means for folding the blanks as they are advanced, a pair of presser plates for engaging the central portions of the blanks, a superstructure on the table, a pair of slidably mounted brackets on the superstructure and from which the presser plates are suspended, and threaded shafts for adjusting said brackets toward and from each other.
15. A blank folding machine including a table, means for advancing the blanks in succession along the table, means for folding the blanks as they are advanced, a presser plate for the middle of a folded blank, a superstructure on the table, a bracket slidably mounted on the superstructure and from which the presser plate is suspended, and means for adjusting said bracket and presser plate laterally of the table.

JAMES H. ROBERTS.
